UNITED STATES PATENT OFFICE.

HARRY C. BREWSTER, OF SHREVEPORT, LOUISIANA.

CASING PROTECTOR.

Application filed February 16, 1926. Serial No. 88,670.

This invention relates in general to casing protectors for use in well drilling, and the object of the invention is to provide a protector of this character which will prevent 5 objects from being dropped or falling down into the well during the drilling operation or at any other time.

Another object of the invention is to provide a protector having these advantages and 10 which permits of the discharge of the cuttings or detritus.

A further object resides in the provision of a protector having these advantages and capacities and which permits the insertion 15 and removal of the drill bit and the motions of the drill stem incidental to drilling while effectively preventing objects from falling into the well.

Other objects and advantages reside in certain 20 novel features of the construction, arrangement and combination of parts which will be hereinafter more fully described and particularly pointed out in the appended 25 claims, reference being had to the accompanying drawings forming a part of this specification, and in which:

Figure 1 is a sectional view showing the invention applied to a well casing,

Figures 2 and 3 are top plan views of the 30 protector showing the different positions of the same, and

Figure 4 is a group view in perspective of the parts of the protector prior to assembly.

Referring to the drawings the numeral 1 35 designates generally a well casing to the upper end of which the protector constituting the present invention is applied. The protector includes a hollow cylindrical body or head, designated at 2, having its lower end 40 threadedly connected to the well casing 1, as indicated at 3. Internally the hollow body 2 is of uniform diameter but adjacent its upper end this hollow body is thickened and tapers outwardly, as indicated at 4. In the 45 tapered portion 4 a number of discharge openings or ports 5 are provided to permit of the discharge of the cuttings or detritus. Due to the outwardly tapering outer wall of the hollow body and to the location of these 50 openings 5 in this peripheral wall there is no likelihood of objects falling in through such ports. This end is also furthered by the narrow and angularly elongated formation of the openings. At its upper end the hollow body 2 has a seat 6 around which a

marginal flange 7 is provided. A fixed ring 8 is mounted on the seat 6 and is held against rotation by means of pins or studs 9 threaded into the upper end of the hollow body 2 and snugly fitted in recesses 10 provided 60 therefor in the underside of the fixed ring 8. The fixed ring 8 is provided with an opening which includes opposite semi-circular or arcuate walls 11 between which the opening is formed with rectangular extensions 12, the 65 end walls of which are beveled, as indicated at 12a. A rotatable cap 15 is mounted on the upper end of the hollow body 2 and this cap has a plate-like body portion 16 which rests on the ring 8 and a depending annular flange 70 17 which is a snug rotating fit around the upper end of the hollow body portion. For the purpose of holding the cap 15 against upward displacement and for limiting the 75 annular movement of the same a pair of slots 18 are provided in the flange 17 and through these slots 18 pins 19 extend, the pins being threaded into the body portion 2. The slots 18 have an angular extent of 90° 80 and the pins 19 are engageable with the end 85 walls of the slots to limit the angular movement of the cap 90°. Since the cap 15 is held down on the body by the pins 19 this cap serves to hold the ring 8 against upward displacement. To facilitate turning of the cap 15 its body portion 16 is provided with an upwardly projecting handle member or pin 20. The body portion 16 of the plate 15 is provided with an opening of the same 90 form and shape as the opening in the ring 8 and the opening of the body portion of the cap has a central portion defined by semi-circular walls 21 and rectangular extensions or end portions 22 defined by parallel vertical side walls and beveled end walls extending 95 at right angles to the vertical side walls, the beveled end walls being indicated at 23.

In one position of the cap 15 relative to the ring 8 the semi-circular walls 21 of the cap opening are complementary to the semi-circular walls 11 of the opening of the ring 8 so that these semi-circular walls 11 and 21 coact to define a complete circular opening through the upper end of the protector and this opening is of such size as to accommodate the drill stem and its couplings and yet prevent the falling of objects into the well. When the walls 11 and 21 are complementary to each other the rectangular extensions of the opening of the cap over- 100 105 110

lie the imperforate portions of the ring and the rectangular extensions of the opening of the ring underlie imperforate portions of the body of the cap, the cap and the ring together constituting a closure for the upper end of the body. In order to permit this closure to present an opening to permit of the insertion and withdrawal of the drill bit the cap and the ring are adjusted to the position shown in Figure 3 wherein the rectangular extensions of the openings of the cap and plate are in vertical alignment.

In order to line up the drill bit with this opening the fixed ring 8 is provided with drill bit camming members 30 which have inclined camming surfaces 31 engageable with the drill bit to turn it into alignment with the rectangular extensions of the opening of the cap and ring.

I claim:—

1. A protector for wells including a hollow body adapted to be secured to the upper end of the well casing and having closure means at its upper end including relatively adjustable members having openings permitting of the passage of the drill stem alone in one adjustment and of the drill bit also in another adjustment, said members overlying the upper end of the well casing in all adjustments whereby they obstruct all portions of the opening at the upper end of the well casing except such portions of said opening as accommodate the drill bit and the drill stem.

2. A protector for wells including a hollow body adapted to be secured to the upper end of the well casing and having closure means at its upper end comprising relatively adjustable members overlying the well casing in all adjustments and having openings permitting of the passage of the drill alone in one adjustment and of the drill bit also in another adjustment, and means carried by the protector and engageable with the drill bit for automatically aligning the drill bit with the openings of the members of the closure when said members are adjusted to permit of the passage of the drill bit.

3. A protector for wells including a hollow body adapted to be secured to the upper end of the well casing and having closure means at its upper end including relatively adjustable members having openings permitting of the passage of the drill stem in one adjustment and of the drill bit in another adjustment, said members overlying the upper end of the well casing in all adjustments, and means for alining the drill bit with the openings of the members

of the closure when the same are adjusted to permit of the passage of the drill bit.

4. A protector for wells including relatively adjustable members mounted to overlie the well casing in all adjustments and having openings permitting of the passage of the drill stem alone in one adjustment and of the drill bit also in another adjustment.

5. A protector for wells including a hollow body having closure means at its upper end adapted to normally permit the passage of the drill stem alone and to be moved to permit the passage of the drill bit also, said hollow body having an outwardly tapering peripheral portion provided with ports permitting of the discharge of the detritus.

6. A protector for use with well casings including a hollow body adapted to have its lower end secured to the upper end of the well casing, a ring fixed to the upper end of the hollow body and having an opening therein, a cap rotatably mounted on the hollow body and overlying the ring, means for limiting the turning movement of the cap, and means for turning the cap, said cap also having an opening co-operable with the opening of the ring to permit of the passage of the drill stem alone in one adjustment and co-operable with the opening in the ring to permit of the passage of the drill bit also in another adjustment.

7. A protector for use with well casings including a hollow body adapted to have its lower end secured to the upper end of the well casing, a ring fixed to the upper end of the hollow body and having an opening therein, a cap rotatably mounted on the hollow body and overlying the ring, means for limiting the turning movement of the cap, means for turning the cap, said cap also having an opening co-operable with the opening of the ring to permit of the passage of the drill stem alone in one adjustment and co-operable with the opening in the ring to permit of the passage of the drill bit also in another adjustment, and drill bit camming members carried by the ring for aligning the drill bit with the openings of the cap and ring.

8. A protector for wells including a hollow body having closure means including relatively adjustable members provided with openings having semi-circular portions complementary in one adjustment to permit of the passage of a drill stem and collars only and also having elongated extensions complementary in another adjustment to permit the passage of the drill bit also.
